UNITED STATES PATENT OFFICE.

CARL B. FARRIS, OF LOS ANGELES, CALIFORNIA.

METHOD AND MEANS FOR PUMPING DEEP WELLS.

Application filed November 6, 1923. Serial No. 673,157.

To all whom it may concern:

Be it known that I, CARL B. FARRIS, a citizen of the United States, and a resident of Los Angeles, in the county of Los Angeles 5 and State of California, have invented new and useful Improvements in Methods and Means for Pumping Deep Wells, of which the following is a specification.

This invention relates to and has for its 10 main object an improved system for pumping deep oil and water wells, whereby the excessive pressures which usually obtain at great depths in the well may be relieved at different stages of operation, so that a more 15 uniform supply of the liquid from the well may be had and a more efficient operation of the pump.

It has been found in the operation of oil 20 and water wells, especially oil wells which usually embody a single plunger, that the pressure created by the high column of liquid above the plunger is so great as to impair the operation of the pump at times, and this condition also requires the frequent 25 changing of the cups on the plungers and adjustment and replacement of other parts.

It is an object, therefore, of this invention to provide a multiple plunger pump arranged with the plunger spaced apart at 30 desirable elevations, approximately five hundred feet more or less, together with means surrounding each of the plungers and extending throughout the limits of operation thereof for receiving and holding volumes of 35 the liquid so as to relieve the pressure in the well, and thereby reduce the weight on the plunger and correspondingly reduce the amount of effort required to operate the pump. This system also eliminates the necessity for frequently adjusting and replacing parts of the plunger.

A more detailed object of this invention 45 is to provide in a deep well pump a tube or working barrel in which is mounted a plurality of plungers connected together by means of sections of rods, commonly called sucker rods, so that the plunger may reciprocate together and to a corresponding extent within the barrel of the pump.

Said plungers are placed at suitable distances apart in the well and it is a further object of this invention to provide at the approximate levels of the plungers a reservoir or casing of cylindrical form, of greater 50 diameter than the working barrel or tube,

and attached thereto, the height and capacity of said reservoir being such that a substantial quantity of the liquid which is lifted by the pump may flow from the barrel into the reservoir for relieving the pressure 60 on the plunger, and on such strokes of the sucker rod the liquid contained in the reservoir will be elevated step by step. In other words, the liquid in the pump instead of being elevated and sustained by a single 65 plunger in a deep well is elevated in a step by step progressive movement from one of the reservoirs to the other, so as to reduce the weight of the liquid on each of the plungers and the resultant pressure within 70 the barrel.

Another object is to provide means in the reservoirs whereby the pressure of the liquid may be relieved by overflowing the liquid from the tops of the reservoirs and also 75 for providing means of communication between the working barrel of the pump and the reservoirs at a point near the lower ends of the reservoirs and below the lowermost limits of the operation of the plunger, whereby the pressure is relieved and the overflow liquid is discharged back into the well.

Still other objects may appear as the description progresses.

I have shown one preferred embodiment of my invention in the accompanying drawings, in which:

Fig. 1 is a fragmentary sectional elevation of a well, showing my improved mechanism embodied therein.

Fig. 2 is a similar sectional elevation on a larger scale, showing one of the reservoirs and one of the plungers in operative relation, and connected with the working barrel of 95 the pump.

Fig. 3 is a sectional plan on the line 3—3 of Fig. 2.

Fig. 4 is a sectional plan on line 4—4 of 100 Fig. 2.

Fig. 5 is an enlarged side elevation of one of the plungers.

In said drawings, W represents the well which may or may not be provided with a casing, the casing being omitted in the views of the drawing. B, B, etc., are a plurality of sections of tubing constituting the working barrel of the pump and adapted to be connected together at their adjacent ends by suitable couplings, not material to this 105 110

invention. R, R, etc., are sections of rods which are adapted to be connected with opposite ends of the plungers P, P, etc., and constitute the sucker rod whereby all of said 5 plungers may be simultaneously operated to a corresponding extent within the barrel B of the pump.

The plungers P are of usual form and character and have the lower ends of each 10 of the rod sections R, R, etc., connected to a valve body V which has ribs 1, 1, etc., formed on the periphery thereof, and openings 2, 2, etc., provided between said openings. A ball valve V' is seated in the space 15 between the ribs 1, 1, etc., of each of the valves and is adapted to close the valve seat on the up-stroke of the plunger, and to open the same on the downstroke thereof. The body P' of each of the plungers has cups 20 3, 3, etc., of leather or other material which serves to seal the plunger within the barrel B.

All of the above described mechanism is typical of oil and water well pumps, except 25 that it is not usual to extend the sucker rods R below the plunger P for the reason that only a single plunger is employed in the obtaining pumping systems. However, it is necessary in my device to provide a fitting 30 F similar in form and character to the valve body V, for attachment to the lower end of the plungers P in each case, so that the lower section of rod R may be attached to the plunger in a manner similar to the upper 35 section of rod.

At the approximate levels of the several plungers in the well I provide a substantially elongated casing C of substantially greater diameter than the barrel B, and providing 40 an annular space S around said barrel for the reception of the liquid in the well. The casing C in each case is mounted on and attached to the sections B, B, etc., of the barrel by means of a suitable reducing 45 union U having a reduced nipple 5 adapted to overlie the joint between the barrel members B, B and an enlarged nipple 6 adapted to overlie the ends of casing C all of said members being threaded together.

50 The member U at the bottom of casing C, and the member U' at the top thereof are substantially the same and are mounted in the same manner, but the member U' is provided with a plurality of openings 7, 7, etc., on the top whereby the space S of the reservoir formed by the casing C is in communication with the well W at the top of said casing. At a point near the lower end of the casing C and below the lowermost limit of 55 operation of the plunger P in each case, I provide a plurality of peripheral openings 8, 8, etc., in the barrel section B which afford communication between the interior of the barrel and the space S of the reservoir. 60

65 Now, in operation the sucker rod com-

posed of the sections R, R is actuated in the usual manner, and to the usual extent for raising and lowering the plungers P, P, etc., to a corresponding extent. On the down stroke of the rod the balls V' are thrust upwardly within the body B so as to open the valve seat, and the liquid at the bottom of the plunger is forced upwardly therethrough and through the openings 2 in the valve body B into that portion of the barrel above 75 the plunger. On the succeeding up stroke of the plunger the pressure in the upper portion of the barrel serves to seat the ball W' in the valve body V and to lift the column of liquid above the plunger to a height corresponding to the length of travel of the plunger. This action is the same as stated in oil and water wells, but where only a single plunger is used a column of oil must be carried within the barrel B of a height 80 corresponding substantially to the depth of the well, and in the case of moderately or extremely deep wells the weight of this column of liquid is so great that it frequently impairs the operation of the pump and 85 requires undue attention to the working parts.

In my system, however, by the employment of a plurality of the plungers P spaced apart at suitable distances, the height of the 95 column of liquid sustained by each of the plungers is limited by the spacing of the plungers, and as the plungers move upwardly the liquid or a portion thereof is discharged through the openings 8, in the wall 100 of the barrels B into the annular space S of the reservoir C at each successive stage in the operation of the pump, and in the case of deep wells where the pressure is substantially increased the surplus liquid will overflow through the openings 7, 7, in the tops 105 of the reservoir C and the same will be discharged back and downwardly into the well, thus relieving the pressure in the several stages where the reservoirs C are provided. 110

At the same time, on the succeeding stroke of the plunger the liquid from the space S of the reservoir will flow back into the barrel B and the same will be elevated through the plunger and into the portion of the barrel thereabove the succeeding strokes of the sucker rod R and the plunger P. Thus, at each stroke of the plunger the pressure is relieved to an extent necessary for effecting the efficient operation of the pump and for preventing undue pressures within the barrel B which tend to impair the operation thereof. 115

It will also be observed by reference to the drawings that the casing C, while of greater diameter than the barrels B are of substantially less diameter than the well W, and the barrel B and casing C are connected together in such a manner that the casings and the tubing sections R may be 120 125 130

withdrawn from the well in units, for the purpose of cleaning, repairs or replacements of parts.

I conceive it to be possible to modify or change the form and arrangement of the several parts contributing to my invention without departing from the spirit thereof, and within the scope of the appended claims.

What I claim is:

- 10 1. In a deep well pump a working barrel, and a plurality of spaced reservoirs attached to the exterior of said barrel, and means for affording communication between said reservoir and the interior of the working barrel near the bottom of the reservoir, and for affording communication between the upper ends of said reservoirs and the well.
- 15 2. In a deep well pump a working barrel, a plurality of spaced reservoirs attached to the exterior of said barrel, means for affording communication between said reservoir and the interior of the working barrel near the bottom of the reservoir, and for affording communication between the upper ends of said reservoirs and the well, and a sucker rod within said barrel provided with a plurality of plungers, said plungers being arranged respectively for operation with relation to said reservoirs.
- 20 3. In a deep well pump a working barrel composed of a plurality of sections, a plurality of casings surrounding said barrel and providing a plurality of reservoirs, means for attaching the ends of said casings to adjoining barrel sections, the lower ends of said reservoirs being closed against communication with the well, and the upper ends thereof having communication with the

well, and the lower ends of said reservoirs being in communication with the interior of said barrel, for the purpose described.

4. In a deep well pump a working barrel composed of a plurality of sections, a plurality of casings surrounding said barrel and providing a plurality of reservoirs, means for attaching the ends of said casings to adjoining barrel sections, the lower ends of said reservoirs being closed against communication with the well, and the upper ends thereof having communication with the well, and the lower ends of said reservoirs being in communication with the interior of said barrel, a sucker rod operatively mounted within said barrel and plungers attached to said rod and operating within said barrel above the points of communication respectively between said reservoirs and said barrel.

5. The method of pumping oil and water wells which consists in lifting the liquid in the well successively to uniformly spaced points, discharging portions of the liquid thus raised into reservoirs for relieving the pressure and for overflowing portions of the liquid from said reservoirs into the well.

6. The method of pumping oil and water wells which consists in lifting the liquid in the well successively to uniformly spaced points, discharging portions of the liquid thus raised into reservoirs for relieving the pressure and for overflowing portions of the liquid from said reservoirs into the well, and thereafter admitting the liquid from said reservoirs to the pump for subsequent elevation to successive points.

CARL B. FARRIS.
